ELECTRIC CONTROL APPARATUS FOR
FUEL BURNERS

Abraham Lincoln Rubel, Des Moines, Iowa, assignor to Penn Electric Switch Co., Des Moines, Iowa, a corporation of Iowa

Application August 15, 1932, Serial No. 628,883

5 Claims. (Cl. 158—28)

An object of my invention is to provide control apparatus for the electric circuit of a fuel burner, the apparatus being comparatively simple and inexpensive to manufacture.

5 A further object is to provide control apparatus including a warp switch which is energized when combustion occurs in order to break the circuit through a heater of a safety switch, so that upon combustion occurring, the safety

10 switch will not thereafter trip out. Still a further object is to provide means whereby the safety switch can be used to trip out for the purpose of providing a lock out type control in which combustion failure itself has the 15 effect of shutting down the automatic operation of the device.

Still a further object is to re-arrange the circuits and contacts slightly so that after combustion failure, a purging period is provided and then the control apparatus is re-cycled for automatic operation.

20 25 Still a further object is to provide control apparatus including a relay which initiates and terminates operation of a fuel burner and which initiates operation of ignition mechanism for the fuel burner, termination of the operation of the ignition mechanism being effected by combustion occurring.

30 35 Still a further object is to provide a control apparatus in which a safety switch heater, a warp switch and a relay are all in circuit with each other, a combustion responsive switch being effective to open the safety switch heater circuit and energize a warp switch heater which warps the switch to a position where it shunts the relay out of the circuit, so that upon combustion failure, current will flow through the safety switch heater, but not through the relay, with the effect of quickly heating the safety switch heater to trip it and thus lock the apparatus in non-operating position.

40 45 Still a further object is to provide another apparatus in which the relay is not shunted out, but the warp switch, upon combustion failure, is allowed to return to initial position for re-cycling the apparatus, such return being slow so as to provide a purging period.

Both the lock out type and the purging period 50 55 type of apparatus are used on a fuel burner so that upon combustion failure occurring, such as caused by a down draft in the furnace, a slug of water in the fuel oil or the like, automatic operation of the apparatus will either stop until the cause has been remedied and the apparatus

reset, or it will re-cycle after a purging period has been provided to allow the draft of the furnace to purge the combustion chamber of any explosive gas caused by the introduction of fuel after combustion fails.

5 With these and other objects in view my invention consists in the construction, arrangement and combination of the various parts of my device, whereby the objects contemplated are attained, as hereinafter more fully set forth, pointed out in my claims, and illustrated in the accompanying drawing, in which:

10 Figure 1 is an electrical diagrammatic view showing my lock out type of control apparatus; and

15 Figure 2 is a similar figure showing the purging period type of apparatus.

20 On the accompanying drawing, I have used the reference numeral 10 to indicate a line switch. A limit switch is shown at 12 which may be temperature or steam pressure operated and which is ordinarily used in control circuits on furnaces and boilers to prevent the furnace or boiler being heated to an excessive degree. Junction boxes are shown at 14 and 16. These form no essential 25 part of my present invention, but are merely provided on the actual switch for the convenience of the electrician when installing and wiring the apparatus. The junction box 16 has terminals indicated as 1, 2, 3 and 4.

30 35 My apparatus further includes a room thermostat 18, a combustion responsive control switch 20, an ignition switch 22 also responsive to combustion, a safety switch 24, a warp switch 26 and a relay 28. At 30 a furnace is shown and the burner therefor is shown more or less diagrammatic at 32. An ignition transformer is shown at 34 and a spark gap at 36. This comprises the ignition mechanism mentioned in my claims.

40 45 In Figure 1, the control switch 20 has contacts 38, 40 and 42. The ignition switch 22 has contacts 44 and 46. The safety switch 24 has contacts 48 and 50. The safety switch includes a heater 52 and a bimetal latch 54, which, when warped to the dotted line position by heat from the heater 52, will permit disengagement of the contacts 48 and 50. The warp switch 26 includes contacts 56, 58 and 60. The warp switch further includes a bimetal actuator 62 for the contact 56 and a warp switch heater 64.

50 55 In Figure 2, the control switch 20 has contacts 38, 41 and 42. The ignition switch has contacts 44 and 46. The safety switch 24 and the warp switch 26 are the same as in Figure 1 except there is no contact 58.

The relay 28 has burner control contacts 66 and 68 and holding contacts 70 and 72.

The control and ignition switches 20 and 22 in both figures are normally in the solid line positions. Upon combustion occurring, bimetal helixes 21 cause movement of the contacts 38 and 46 to their dotted line positions. The combustion responsive switches 20 and 22 are of the ordinary type commonly termed a stack switch having a 10 slip connection to cause immediate movement of the movable contacts from one position to another and thereafter permitting slippage. The warp switches 26, when heated by energization of the heater 64, warp to the dotted line positions.

15 In conjunction with my apparatus, I provide a transformer 14 having a primary winding 78 and a secondary low voltage winding 79, so that the relay and the mechanism for controlling it therefore need not be constructed for high voltage 20 current.

Operation of lock out control apparatus

Referring to Figure 1, the room thermostat 18 is in open position. When it calls for heat, the 25 current may be traced from the secondary winding 79, through the room thermostat 18, through the closed contacts 38 and 40, through the safety switch heater 52, through the warp switch 26 and its contacts 56 and 60 and through part of the 30 relay 28 and return. This energizes the relay so that its armature 28a is attracted to the dotted line position, whereupon high voltage current from the left side of the line switch 10, through the limit switch 12, the safety switch 24 and the 35 contacts 66 and 68 flows to the burner 32 and return. Also, the high voltage current flows from the contact 68, through the ignition contacts 44 and 46 to the ignition transformer 34 and return. This causes a high tension spark at the spark gap 40 36.

40 Energization of the relay 28 also closes the contacts 70 and 72 so that current from the room thermostat 18 is supplied through the entire coil of the relay 28 and return. Thus the relay is held in closed position after once being energized.

45 Upon combustion occurring, the contacts 38 and 46 of the control switch 20 are separated for opening the circuit through the safety switch heater 52 so that it will not open the safety switch 24, which would occur after a period of time if combustion did not separate the contacts. This opens the first circuit through the relay 28, but the holding contacts 70 and 72 retain the relay in energized position. Combustion occurring also separates the ignition contacts 44 and 46 to terminate 50 operation of the ignition mechanism. Combustion occurring also closes the contacts 38 and 42 of the control switch 20 which energizes the warp switch heater 64. This will cause the switch 26 to warp to the dotted line position, engaging contact 56 with contact 58.

55 Subsequently, upon combustion failure, the contact 38 will re-engage the contact 46 for energizing the safety switch heater 52 without passing the current through the relay coil 28 because the contacts 38-46 are closed a material time period before the warp element 62 has cooled sufficiently to open the contacts 56 and 58 in the circuit of the heater 52.

60 This results in a much quicker heating of the heater 52 for immediately opening the safety switch 24 contacts due to the fact that there is less resistance in series with the heater 52. The apparatus is now locked out inasmuch as it cannot be re-cycled except after the safety switch 24 has been manually reset.

Operation of purging period control apparatus

In Figure 2, closing of the contacts in the room thermostat 18 will establish a circuit through the safety switch heater 52, the warp switch 26 and its contacts 56 and 60, the relay 28 and return. This initiates operation of the burner and of the ignition mechanism, termination of the ignition mechanism being through separation of the contacts 44 and 46, the same as in Figure 1.

10 Upon combustion establishment, the contact 38 engages the contact 41 for establishing the holding circuit through the contacts 70 and 72 which have been engaged by energization of the relay 28, but not rendered effective because of the normal full 15 line positions of the contacts 38 and 41. Combustion establishment also closes the circuit through contacts 38 and 42 for energizing the warp switch heater 64 and causing the warp switch 26 to warp to its dotted line position. This opens the circuit 20 through the safety switch heater 52.

Upon combustion failure, the contact 38 separates from the contacts 41 and 42, thus de-energizing the holding circuit through the contacts 70 and 72 for terminating operation of the burner 25 32 and de-energizing the warp switch heater 64. Thereafter the heater 64 will gradually cool down and so will the bimetal element 62 of the warp switch 26. It will finally cause engagement of the contacts 56 and 60 which re-establishes 30 a circuit through the upper portion of the relay coil to re-cycle the apparatus by re-initiating operation of the burner 32. The period of time during which the bimetal element 62 moves from the dotted line to the full line position 35 provides a period during which the furnace is purged of gases which might explode when the contacts 66 and 68 are re-engaged to re-establish ignition as well as re-initiate operation of the burner.

40 In either form of my apparatus, I provide a warp switch for opening the safety switch heater circuit and for controlling the circuit so that either a lock out (in Figure 1) or a purging period operation results (in Figure 2). Although 45 I have shown the transformer 14, it will be obvious that the entire apparatus may be operated by high voltage current and the transformer eliminated.

50 Some changes may be made in the construction and arrangement of the parts of my device without departing from the real spirit and purpose of my invention, and it is my intention to cover by my claims, any modified forms of structure or use of mechanical equivalents, which may 55 be reasonably included within their scope.

I claim as my invention:

1. In combination with an electrically operated fuel burner, a control system comprising a relay operable when energized to close the burner 60 circuit to initiate operation, a room thermostat controlling energization of said relay, a thermal time limit cutout switch including a resistance heater controlling said system, a switch having a warp element, a heater, first contacts which 65 are closed when said element is cold and second contacts which are closed when said element is heated, combustion responsive switching means having contacts closed in the absence of combustion and other contacts closed in the presence 70 of combustion, a circuit including the room thermostat, the contacts of the combustion responsive switching means closed in the absence of combustion, the cutout switch heater, said first contacts and said relay, a second circuit includ- 75

- ing the heater for said warp element and the contacts of the combustion responsive switching means closed in the presence of combustion and a third circuit including the heater of said cutout switch and said second contacts, said warp element moving slowly when cooling whereby upon combustion failure, said cutout switch is quickly actuated to shut down the system.
2. In combination with an electrically operated fuel burner, a control system comprising a relay operable when energized to close the burner circuit to initiate operation, a room thermostat controlling energization of said relay, a thermal time limit cutout switch including a heater controlling said system, a switch having a warp element, a heater, first contacts which are closed when said element is cold and second contacts which are closed when said element is heated, combustion response switching means having contacts closed in the absence of combustion and other contacts closed in the presence of combustion, a circuit including the room thermostat, the contacts of the combustion responsive switching means closed in the absence of combustion, the cutout switch heater, said first contacts and said relay, said relay having holding contacts to maintain the relay energized when said contacts of the combustion responsive switching means closed in the absence of combustion are opened by the presence of combustion, a second circuit including the heater for said warp element and the contacts of the combustion responsive switching means closed in the presence of combustion and a third circuit including the heater of said cutout switch and said second contacts, said warp element moving slowly when cooling whereby upon combustion failure, said cutout switch is quickly actuated to shut down the system.
3. In a system having electrically controlled fuel feeding and ignition means, a main control switch, an electrically actuated time limit cutout switch operable to open in time periods varying in accordance with its rate of energization, switching mechanism including reactances and a combustion controlled switch, and circuit connections including the foregoing elements controlling energization of the fuel feeding and ignition means and the energization of the time switch and rate thereof and operable upon a demand for heat and closure of the main switch to: (1) energize the fuel feeding and ignition means and energize the time switch at a predetermined rate; (2) deenergize the ignition means and time switch upon the establishment of combustion; and (3) reenergize the time switch at a higher rate while maintaining energization of the fuel feeding means upon a failure of flame 5
4. In combination with a fluid fuel burner and its fuel feeding means, a control system including in circuit a main control member, an electrical safety time switch whose timing interval 10 varies with the rate at which it is energized for discontinuing fuel feed to the burner at the conclusion of the timing interval, a combustion responsive device, and means responsive to the main control member for simultaneously initiating operation of said burner and energizing said time switch at a first rate, and cooperating with the combustion responsive device to deenergize said time switch upon the successful establishment of combustion, and to reenergize said time 20 switch at a second rate higher than said first rate upon the occurrence of subsequent flame failure, whereby said time switch provides a longer timing interval upon initiation of operation of the burner than is provided upon the 25 occurrence of flame failure.
5. In a system having electrically controlled fuel feeding and ignition means, a main control switch, an electrically actuated time limit cutout switch operable to open in a time period varying in accordance with the rate of current flow therethrough, a plurality of switches, switching mechanism for actuating said switches including reactances and a combustion responsive thermostat, and circuit connections including the foregoing elements controlling energization of the time switch and the fuel feeding and ignition means and operable upon a demand for heat and closure of the main switch to: (1) energize the fuel feeding and ignition means and energize the time switch in series with a material reactance 30 and thereby at a relatively low rate; (2) de-energize the fuel feeding and ignition means and the time switch upon the establishment of combustion; and (3) upon combustion or flame failure 35 during normal operation to re-energize said time switch at a relatively high rate while maintaining energization of the fuel feeding means whereby said time switch will quickly open to render the system inoperative. 45
